UNITED STATES PATENT OFFICE

JAMES R. COE, OF WATERBURY, CONNECTICUT, ASSIGNOR TO THE AMERICAN BRASS COMPANY, OF WATERBURY, CONNECTICUT, A CORPORATION OF CONNECTICUT

ADJUSTING MEANS FOR ROLLING-MILL ROLLS

Application filed April 19, 1928. Serial No. 271,148.

This invention relates to rolling mills, and particularly to an improved means for adjusting the adjustable roll for determining the thickness of the metal to be rolled, and has for an object to provide an improved adjusting means which will positively and accurately hold the roll in adjusted position.

It is also an object of the invention to provide a roll adjusting means which is very simple in construction and is easily operated.

With the above and other objects in view, the invention consists in certain novel features of construction, combinations and arrangements of parts as will be more fully described, a construction illustrating one form of the invention being shown in the accompanying drawings. In these drawings,

Fig. 1 is an end elevation of the upper portion of the roll housing showing my invention as applied thereto.

Fig. 2 is a cross section substantially on line 2-2 of Fig. 1 on a somewhat larger scale, and

Fig. 3 is a front elevation of the upper part of the roll with my invention applied thereto, a portion of the housing being broken away to more clearly show the construction.

The arrangement illustrated comprises the usual housings or frames 5 having the upright rectangular opening 6 forming guides for the bearings or supporting members 7 for the necks 8 of the rolls 9. Guide plates 10 retain these blocks or supporting members in the housings.

A transverse opening 11 is bored through the upper part of the housing, preferably so that it opens at its lower side through the top connecting portion 12 of the housing. This bored opening is preferably at substantially right angles to the axis of the rolls and horizontal. Mounted between the housing and the bearing or supporting member 7 is a pair of wedges 13 and 14. The lower wedge member 13 is substantially rectangular in cross section and is recessed into the upper wall of the member 7 as shown at 15, and it has a cross key 16 seated in a similar cross groove 17 in the top of the member 7. This wedge is, therefore, permanently held in proper position on the member 7. Its upper wall 18

is inclined as indicated in Fig. 1, and if preferred instead of this inclined wall running continuously the entire length of the wedge this wedge may be recessed as shown at 19 intermediate its ends to reduce the friction between this wedge and the upper wedge 14.

The upper wedge 14 is of general cylindrical form in cross section and is flattened at its lower side 20. This flat surface is inclined to the axis of the wedge at the same angle as the surface 13 of the lower wedge. The diameter of the wedge 14 is the same as that of the bore 11 so that the curved upper wall of the wedge has a continuous and uniform bearing in this bored opening. It will be apparent that as the wedge 14 is forced inwardly or to the left, as viewed in Fig. 1, the camming action of the inclined surfaces 13 and 20 between the two wedges will force the roll supporting member 7 downwardly to adjust the relative positions of the rolls and determine the gauge of the stock rolled.

Means is provided for conveniently adjusting the wedge member 14 in or out. In the arrangement shown the wedge 14 is provided with a tapped opening leading from its outer end in which is threaded an adjusting screw 21 mounted in a suitable thrust bearing 22 mounted in the housing. Mounted on the outside of the housing is a bracket 23 and mounted on the screw 21 is a bevel gear 24. There is a bracket 23 in each housing on the front side wall thereof carrying a horizontally extending shaft 25 which has beveled pinion 26 meshing with the gears 24. For the purpose of ease of manufacture and in mounting, the shaft 25 may be made in sections connected by interlocking collars 27, and suitable hand wheels 28 are provided for operating the shaft 25 and through it the adjusting screws 21 to shift the wedge members 14 and adjust the upper roll 9 as will be readily understood. This construction provides the same uniform and simultaneous operation for the two wedges 14 at the opposite ends of the roll. If the clutch 27 is disconnected the two wedges may be independently adjusted.

It will be apparent from the foregoing description that in this arrangement of the

wedges there is an absolutely uniform bearing provided throughout the entire length of the upper wedge irrespective of the roll position in the housing. There is also always a uniform bearing between the two wedge members 13 and 14 as the member 14 may turn on its axis in its bearing in the housing. This, therefore, makes a very effective adjusting means which is always uniform in operation, and the strain of the rolling operation is carried by the wedge members instead of the threads of the adjusting screws as in the old form of adjustment.

15 Having thus set forth the nature of my invention, what I claim is:

1. In a rolling mill including a housing member and a roll supporting member, a pair of wedges between the said members, one 20 of said wedges being substantially rectangular in cross section, cooperating means between said wedge and one of the members to retain the wedge in position, the other member being provided with a cylindrical 25 guideway extending transverse the axis of the roll, the other wedge being provided with a cylindrical wall to fit said guideway and a flat side to engage the other wedge, and a screw threaded in said second wedge for 30 shifting said second wedge and concentric with said cylindrical wall so that said wedge can turn in the guideway about the axis of the screw.

2. In a rolling mill including a housing member and a roll supporting member, a substantially cylindrical wedge having a flat surface at one side inclined to the axis of the wedge, one of said members being provided with a cylindrical guideway to fit the 40 curved wall of the wedge and extending transverse the axis of the roll, means on the other member cooperating with said flat surface, and an adjusting screw connected with said wedge concentric with its longitudinal 45 axis so that said wedge can turn in the guideway about the axis of the screw, said screw being adapted for longitudinally shifting the wedge to adjust the position of the roll.

3. In a rolling mill, a housing provided 50 with a transverse cylindrical opening forming a cylindrical guideway extending transverse the axis of the roll, a substantially cylindrical wedge mounted in said guideway having a flat surface on one side inclined to 55 the axis of the wedge and a longitudinal threaded opening concentric with its longitudinal axis so that the wedge may turn in the guideway about the axis of a screw in said 60 opening, a roll supporting member movable in the housing, a substantially rectangular wedge on said member having an inclined side wall engaging that of the first wedge, and an adjusting screw in said threaded opening for longitudinally shifting the first wedge

to adjust the position of the supporting member.

4. In a rolling mill, an upright housing, a vertically movable roll supporting member in said housing, said housing being provided with a transverse cylindrical opening, a similarly shaped wedge mounted in said opening and having a flattened side wall inclined to the axis of the wedge, a similarly inclined wall on the supporting member cooperating with that on the wedge, and an adjusting screw connected to the wedge concentric with its longitudinal axis so that the wedge may turn in the opening about the axis of the screw, said screw being adapted for shifting the wedge.

5. In a rolling mill, an upright housing, a vertically movable roll supporting member in said housing, said housing being provided with a transverse cylindrical opening, a substantially cylindrical wedge mounted to slide in said opening and having a flattened side wall inclined to the axis of the wedge, a rectangular wedge mounted on the supporting member having an inclined wall cooperating with that of the first wedge, said first wedge being provided with a tapped opening leading from one end thereof concentric with its longitudinal axis so that the wedge may turn in the cylindrical opening about the axis of a screw in the tapped opening, and an adjusting screw threaded in said tapped opening.

In testimony whereof I affix my signature.
JAMES R. COE.
